CLIP FOR REMOVING EXPLOSIVELY-OPERATED WEDGE-TYPE ELECTRICAL CONNECTORS

Carl Raymond Hedberg, Harrisburg, Pa., assignor to
AMP Incorporated, Harrisburg, Pa.

Filed Oct. 20, 1965, Ser. No. 87,622

Term of patent 14 years

(Cl. D54—13)

FIGURE 1 is a perspective view of a clip for removing explosively-operated wedge-type electrical connectors showing my new design;

FIGURE 2 is a top plan view thereof;

FIGURE 3 is a side elevational view thereof;

FIGURE 4 is a front end view thereof; and

FIGURE 5 is a rear end view thereof.

I claim:

The ornamental design for a clip for removing explosively-operated wedge-type electrical connectors, substantially as shown.
